UNITED STATES PATENT OFFICE

MICHAEL PARIDON, OF BARBERTON, OHIO, ASSIGNOR TO THE DIAMOND MATCH COMPANY, OF BALTIMORE, MARYLAND, A CORPORATION OF MARYLAND

MACHINE FOR PACKING MATCHES

Application filed May 12, 1931. Serial No. 536,777.

This invention relates to machines for packing matches in boxes, and particularly machines whereby so-called "protection strips" are applied to the filled boxes.

The object of the invention is to provide simple and efficient means whereby the match filled boxes and the protection strips therein are relatively shifted in such a manner as to position the strips above the heads of the matches in the respective boxes.

The invention may be described as a modification of the mechanism illustrated in Letters Patent of the United States No. 1,168,906, dated January 18, 1916, wherein a match packing machine is equipped with an intermittently movable conveyer for the filled boxes including the protective strips, and with a reciprocating member which bears upon the protection strip of each succeeding box with an ironing effect longitudinally of the strip in a manner to smooth the protection strip and to level and compact the matches within the box while the conveyer is at rest.

According to the present invention in the form herein illustrated, a reciprocating pressure element is arranged and adapted to bear upon the protection strip and the matches in each succeeding box before the conveyer comes to rest, thereby not only straightening or settling the matches in the box, but also temporarily holding the strip while the box is moving, in consequence of which latter effect the tray moves relatively to the strip in a manner to position the trailing side of the box at or against the strip and with the match heads beneath the latter, as will be herein-after described, the scope of the invention being expressed in the appended claims.

In the drawing—

Figure 1 is a plan of a part of a match packing machine embodying my invention, a portion of the pressure element overlying one of the box trays being broken away.

Fig. 2 is a partial side elevation of the machine, the box trays and protection strips being in section.

Fig. 3 is a transverse vertical section, as on the line 3—3 of Fig. 1.

Fig. 4 is a perspective of the pressure element and adjuncts.

Fig. 5 is a view of the pressure element and two underlying box trays in their relative positions during the final movement of the trays in a step thereof immediately before the descent of such element.

Fig. 6 is a similar view illustrating the relative positions of the present element and the underlying trays after the descent of the element and the completion of the step movement of the trays, showing the protection strips positioned above the heads of the matches.

Referring to the drawing, 10 designates a part of the bed or table, and 11 a part of the intermittently-movable tray conveyer comprising an endless chain of links provided with holders 12 for the box trays 13. These trays are filled with matches upon which protection strips 14 are imposed in the usual manner. The succession of spaced trays are advanced by the conveyer to match arranging mechanism including two spring-controlled swinging members 15 which act against the ends of matches which may be projecting beyond the sides of the trays and push such matches into their respective trays. This mechanism also includes a vertically reciprocating T-shaped plunger 16 the arms 17 of which are operatively connected with the swinging members.

18 designates a pressure foot comprising in the present instance an H-plate 19 the parallel members of which are spaced to overhang two adjacent trays borne by the conveyer and are provided on their under surfaces with corrugated rubber pads 20 having relatively wide bearing surfaces, each approximating in area the top of a filled tray.

The connection between the members of the plate 19 has formed thereon or secured there-to a slotted frame 21 which, similarly to the ironing member described in Patent No. 1,168,906, is carried by the free end of a reciprocative arm 22. The opposite end of this arm is rotatably fitted to the crank-shaped or eccentric end of a power driven shaft 23, and hence the arm together with the foot is rapidly reciprocated longitudinally of the protection strips and transversely of the matches contained in the trays.

The duplex pressure foot is moved upon the protection strips of two adjacent trays before the box conveyer comes to rest, that is, during the final movement in a step of the conveyer, and then the foot is raised above the path of the trays and lowered in the next succeeding step movement of the conveyer, and so on. Hence in the intermittent progress of the conveyer the matches and the protection strips of each tray are subjected to the successive action of the two reciprocating rubber pads, which by their contact with the matches perform the function of straightening or settling the matches in the respective trays, and which pads by their frictional contact with the protection strips and their relatively wide bearing surfaces prevent the advancement of the strips with the trays and also prevent cocking of the matches in the trays during the relative movement of the trays and pads. Consequently the trays move relatively to their respective strips, and the trailing sides of the trays, (where the match heads lie) are positioned against the strips so that such strips effectually overlie and protect the match heads.

In the present instance the lowering and raising of the pressure foot in timed relation to the travel of the box conveyer is effected by an angular arm 24, one member of which is secured to an arm 17 of the plunger 16, the other member freely entering the slot or opening of the frame 21. In the upward stroke of the plunger, while the conveyer is at rest the angular arm 24 impinges against the opposing top of the slot and thus raises the frame 21 and the attached pressure foot, and in the initial descent of the plunger 16, while the conveyer is moving, the arm 24 and frame permit the foot to drop by gravity upon the contents of the underlying trays and to remain thereon during the final movement in a step of the conveyer.

Without limiting my invention to the specific details of construction herein disclosed, what I claim is—

1. In a match packing machine having means for intermittently feeding box trays filled with matches and provided with protection strips, means having a relatively wide bearing surface movable upon the protection strips of each succeeding tray during a step or movement of the tray before it comes to rest, and operative to hold the protection strip of the tray in opposition to such step or movement, whereby the trailing side of the tray, where the match heads are located, is positioned in close relation to the strip.

2. In a match packing machine having means for intermittently feeding box trays filled with matches and provided with protection strips, a pressure element having a relatively wide bearing surface arranged to bear upon the protection strip of each succeeding tray while the tray is moving, thereby hold-

ing the strip in opposition to the movement of the tray, and means for periodically moving said element to and from the top of the tray.

3. In a match packing machine having means for intermittently feeding box trays filled with matches and provided with protection strips, a pressure element having a relatively wide bearing surface movable upon the protection strip of each succeeding tray during each movement of the feeding means, thereby holding the strip in opposition to the movement of the tray, means for periodically moving said element to and from the protection strip, and means for reciprocating said element longitudinally of the protection strip.

4. In a match packing machine having means for intermittently feeding a succession of spaced box trays filled with matches and provided with protection strips, a pressure element including two spaced pads having relatively wide bearing surfaces movable upon the protection strips of two adjacent trays during each movement of the feeding means, thereby holding the strips in opposition to the movement of the trays, means for periodically moving said pressure element to and from the protection strips, and means for reciprocating said element longitudinally of the protection strips.

Signed at Barberton, in the county of Summit and State of Ohio this 8th day of May A. D. 1931.

MICHAEL PARIDON.
